UNITED STATES PATENT OFFICE.

MAX JACOB, OF BERLIN, GERMANY, ASSIGNOR TO THE NATIONAL CASH REGISTER COMPANY, OF DAYTON, OHIO, A CORPORATION OF OHIO, (INCORPORATED IN 1906.)

CASH-REGISTER.

1,100,017.

Specification of Letters Patent. Patented June 16, 1914.

Application filed August 25, 1911. Serial No. 645,969.

To all whom it may concern:

Be it known that I, MAX JACOB, a subject of the Emperor of Germany, residing at Berlin, Germany, in the Kingdom of 5 Prussia and Empire of Germany, have invented certain new and useful Improvements in Cash-Registers, of which I declare the following to be a full, clear, and exact description.

10 This invention relates to accounting machines and more particularly to the recording mechanism thereof.

Heretofore machines with printing attachments having normally inoperative check issuing mechanism have been placed upon the market equipped with devices that coöperate with certain manipulative devices in such a manner, that, when said manipulative devices are operated, the check issuing mechanism will be rendered operative. The objection to this class of machines has been that it is impossible to alter the control of the 20 check issuing mechanism without reconstructing the machine.

25 It is the principal object of this invention to provide adjustable mechanism which at the will of the operator may be brought into coöperative relation with one or more of a plurality of manipulative devices so as to render the check issuing mechanism operative when said manipulative devices are operated, with which the adjustable mechanism is brought into coöperative relation.

With this and incidental objects in view 35 the invention consists in certain novel features of construction and combinations of parts the essential elements of which are set forth in appended claims and a preferred form of embodiment of which is hereinafter shown with reference to the drawings which accompany and form part of this specification.

40 Of said drawings: Figure 1 is a side elevation partly broken away of the recording mechanism of a machine of the type shown in Patent No. 580,378, granted April 13, 1897, to Cleal and Reinhard with the improvement applied thereto. Fig. 2 is an enlarged sectional view through the plate carrying the adjustable devices which control the check issuing mechanism. Fig. 3 is a 45 sectional view through a machine of the type mentioned in the aforesaid Cleal and Reinhard patent.

For the purpose of illustration, this invention has been shown applied to a machine of the type shown in the Cleal and Reinhard patent but it is to be understood that this invention is not limited to this type of machine but with equal facility may be 50 applied to other well known forms of accounting machines.

Described in general terms, this invention comprises a plurality of devices which are adjustable singly into and out of coöperative relation with a bank of companion special keys, which may represent departments or different classes of transactions. Upon the depression of any one of the keys with which its companion adjustable device is in 55 coöperative relation a plate carrying said devices will be moved rearwardly. This plate is connected by suitable intervening mechanism to one of a pair of feed rollers, which is normally out of coöperative relation with its companion roller, but which upon the movement of said plate will be brought into coöperative relation therewith, so that, when said rollers are subsequently 60 rotated a check strip will be fed into position to have printed thereon suitable characters from a set of type carriers after which that portion of the strip containing printed matter will be severed from the rest of the strip and ejected from the machine.

65 The machine to which this improvement has been shown applied is provided with a plurality of banks of amount keys 1, each bank of keys controlling the differential movement of a segment 2. This segment 2 meshes with a gear 3, which in turn meshes with gears 4 and 5 that actuate the registering and indicating mechanisms respectively. Each one of these gears 3 is connected to the inner end of one of a series of nested sleeves 70 6, the outer ends of which carry type carriers 7 (Fig. 1). These sleeves surround a shaft 8 which is given a complete rotation at each operation of the machine, as is fully 75 shown and described in the aforementioned Cleal and Reinhard patent. Secured to this shaft 8 adjacent to the type carriers 7 is a gear 9, which through gears 10, 11 and 12 80 drive feed rollers 13 and 14 which rollers are connected to the gears 11 and 12 respectively. These rollers 13 and 14 are normally inoperative, but when in operative 85 condition they will feed a check strip 15

from a supply roll 16 through a chute 17 to a position upon a table 18 adjacent to the type carriers 7, so that when the table 18 is reciprocated a platen 19 carried by said table will take an impression upon a check strip from said type carriers. The table or platen carrying frame 18, as is well known in the art and fully described in the aforementioned patent, is reciprocated three times upon each rotation of the shaft 8, which reciprocations are for the following purposes; first, inking the type carriers; second, taking an impression upon a check strip, and third, the taking of an impression upon a record strip 20 carried by the table and which is fed from a supply roll 21 to a storage roll 22, by means not shown, upon the movement of the table or platen carrying frame 18.

20 The check strip 15 in passing from the feed rollers to the table 18 passes through a stationary knife 24 secured to the frame of printing mechanism and over a movable knife carried by the table 18. Upon the second reciprocation of the table 18, which is for the purpose of taking an impression upon the check strip when the latter is fed upon said table, the knives 23 and 24 will sever the strip, and immediately thereafter 25 suitable mechanism, (not shown) but which is fully shown and described in the aforementioned patent will eject the severed portion of check strip.

All of the parts and functions thereof as 35 heretofore described are old and well known in the art and for a further description of same reference may be had to the aforementioned Cleal and Reinhard patent. With this general understanding of the operation 40 of the type of machine to which this invention has been applied, a description of the invention as applied thereto will now be given.

The chief object of the present invention 45 is to provide a flexible control of the check issuing mechanism, that is to provide means whereby, at the will of the operator, the check issuing mechanism may be placed under the control of any one of a plurality of manipulative devices.

A bank of special or department manipulative devices in the form of keys 36 is located at the left hand end of the machine, and these keys control a type carrier 7 in 55 a manner similar to the previously described amount keys 1. Adjacent to this bank of special keys is a plate 33 which is supported by arms 29 and 32, which in turn are pivotally mounted upon the frame work of the machine. The free end of arm 29 is provided with a pin 30 which plays in an elongated slot 31 of the arm 32, which construction permits the simultaneous rocking of the arms 29 and 32 when the plate 33 carried 60 by said arms is moved rearwardly.

Pivots mounted upon the plate 33 are a plurality of pawls 34, one for each special key, which are adjustable into and out of co-operative relation with pins 35 projecting from said special keys 36. The free ends of 70 said pawls play between pins 42 projecting from the plate 33, and said pawls are frictionally held in their adjusted positions by springs 38 interposed between the heads of screws 37, upon which said pawls are 75 mounted, and the hubs of the pawls (Fig. 2).

The plate 33 is provided with radial slots 50, through which the key pins 35 pass if the pawls 34 are adjusted out of co-operative relation therewith. To facilitate the adjustment of said pawls a flange 43 projects laterally from each one of same, by which flanges the attendant may move any of the pawls into or out of co-operative relation with the pins 35 of the special keys 36. A 85 lid 40 pivoted to the machine normally covers the adjustable pawls and is provided with a lock 41 so as to prevent unauthorized manipulation of the adjustable pawls or devices 34.

90 By reference to Fig. 1 it will be seen that the second, fifth and sixth pawls 34 counting from the upper end of the plate 33 are in co-operative relation with the pins 35 of the companion special keys, while the remaining 95 pawls are out of such relation. It is obvious from this that if either the second, fifth or sixth key is operated, the plate 33 carrying the pawls will be moved rearwardly, which rearward movement, as hereafter described, will render the feed rollers operative.

The feed rollers 13 and 14, as previously stated, are normally inoperative, and the lower roller 14 is mounted upon a movable 105 bearing 25, which has eccentric studs 26 projecting from each end thereof into the frame work of the printing mechanism. Projecting downwardly from the inner one of the eccentrics 26 is an arm 27, which is connected 110 by link 28 to the arm 29, which supports one end of the movable plate 33.

115 From the above description it will be seen that when one of the special keys 36 is depressed, with which its pawl 34 is in co-operative relation, the plate 34 will be moved rearwardly and through the arm 29, link 28 and arm 27 rotate the eccentrics 26 in a clock-wise direction, which movement, through the bearing 25, will raise the roller 120 14 into co-operative relation with the roller 13, so that upon the rotation of shaft 8 the said rollers will feed the check strip to the table 18 to have an impression taken thereon from the type carriers 7.

125 It is obvious from the above description that a very simple mechanism is provided for altering the control of the check issuing mechanism so that at the will of the operator the said mechanism may be ren-

dered operative or inoperative upon the entering of any one of a plurality of transactions.

While the form of mechanism herein shown and described is admirably adapted to fulfil the objects primarily stated, it is to be understood that it is not intended to confine the invention to the one form of embodiment described but that it is susceptible of embodiment in various forms all coming within the scope of the claims which follow.

What is claimed is:

1. In an accounting machine, the combination with a single check issuing mechanism, of an operating mechanism therefor constructed to be operated whether or not a check is to be issued, a series of manipulative devices, and adjustable devices coöperating with the manipulative devices for determining whether a check is to be issued by the check issuing mechanism upon the operation of the operating mechanism.

2. In an accounting machine, the combination with a single check issuing mechanism, of an operating mechanism therefor constructed to be operated whether or not a check is to be issued, a bank of keys, and devices adjustable at will and coöperating with the keys for determining whether a check is to be issued by the check issuing mechanism upon the operation of the operating mechanism.

3. In an accounting machine, the combination with a single check issuing mechanism, of an operating mechanism therefor constructed to be operated whether or not a check is to be issued, a bank of depressible keys, and devices adjustable at will in the path of said keys for the purpose of placing the check issuing mechanism in operative condition when any of the keys is depressed so that upon the operation of the operating mechanism a check will be issued.

4. In an accounting machine, the combination with a pair of rollers for feeding a check strip, of an operating mechanism for said rollers, a bank of keys, and devices adjustable at will and coöperating with the keys for determining whether the check strip is to be fed by the feed rollers upon the operation of the operating mechanism.

5. In an accounting machine, the combination with a pair of rollers for feeding a check strip, of an operating mechanism for said rollers, a bank of keys, devices adjustable at will and coöperating with the keys for determining whether the check strip is to be fed by the feed rollers upon the operation of the operating mechanism, and means actuated by the operating mechanism for severing the strip into checks.

6. In an accounting machine, the combination with a pair of normally inoperative rollers for feeding a check strip, of an operating mechanism for said rollers con-

structed to be operated whether or not the strip is to be fed, a bank of keys, and devices adjustable at will and coöperating with the keys for rendering the feed rollers operative so that the check strip will be fed by the actuation of the operating mechanism.

7. In an accounting machine, the combination with a type carrier for recording upon a check strip, of normally inoperative means for feeding the strip to the type carrier, an operating mechanism for the feeding means constructed to be operated whether or not the strip is to be fed, a bank of keys, and devices adjustable at will and coöperating with the keys for rendering the feeding means operative so that the check strip will be fed by the actuation of the operating mechanism.

8. In an accounting machine, the combination with a type carrier for recording upon a check strip, of normally inoperative means for feeding the strip to the type carrier, an operating mechanism for the feeding means constructed to be operated whether or not the strip is to be fed, a bank of keys, devices adjustable at will and coöperating with the keys, for rendering the feeding means operative so that the check strip will be fed by the actuation of the operating mechanism, and means actuated by the operating mechanism for severing the check strip.

9. In an accounting machine, the combination with a type carrier for recording upon a check strip, of normally inoperative rollers for feeding the strip to the type carrier, an operating mechanism for the feeding rollers constructed to be operated whether or not the strip is to be fed, a bank of depressible keys, a movable plate mounted adjacent to the keys and having connections for rendering the feed rollers operative when said plate is moved, and devices adjustable at will mounted upon the plate and coöperating with the keys for the purpose of moving the plate when a key is operated so that the check strip will be fed by the actuation of the operating mechanism.

10. In an accounting machine, the combination with a type carrier for recording upon a check strip, of normally inoperative rollers for feeding the strip to the type carrier, a bank of depressible keys, a movable plate mounted adjacent to the keys and having connections for rendering the feed rollers operative when said plate is moved, devices mounted upon the plate and adjustable at will into coöperative relation with the keys so that when the keys are depressed the plate and connections will be moved.

11. In an accounting machine, the combination with a check issuing mechanism, of an operating mechanism therefor constructed to be operated whether or not a

check is to be issued, a depressible key, an adjustable device coöperating therewith for determining whether a check is to be issued by the check issuing mechanism upon the operation of the operating mechanism, and frictional means for holding said device in its adjusted position upon successive operations of the key and the operating mechanism until it is moved out of adjustable position.

12. In an accounting machine, the combination with a check issuing mechanism, of an operating mechanism therefor constructed to be operated whether or not a check is to be issued, a depressible key, an adjustable device coöperating with said key for determining whether a check is to be issued by the check issuing mechanism upon the operation of the operating mechanism, 15 a movable plate upon which the adjustable device is mounted, and frictional means for holding said device in its adjusted position upon the movable plate.

13. In an accounting machine, the combination with a ticket issuing mechanism, of an operating mechanism therefor constructed to be operated whether or not a check is to be issued, a series of manipulative devices, adjustable devices coöperating with the manipulative devices for determining whether a check is to be issued by the check issuing mechanism upon the operation of the operating mechanism, and locking means for preventing the adjustment of said

adjustable devices and constructed to be un- 35 locked to permit the latter to be adjusted.

14. In an accounting mechanism, the combination with a severing mechanism for severing checks from their record strip, a feeding mechanism for said record strip, operating mechanism therefor constructed to be operated whether or not a check is to be issued, a depressible key, an adjustable device coöperating therewith for determining whether a check is to be issued by the check issuing mechanism upon the operation of the operating mechanism, and frictional means for holding said device in its adjusted position.

15. In an accounting mechanism, the combination with a check issuing mechanism, of an operating mechanism therefor constructed to be operated whether or not a check is to be issued, a series of manipulative devices, and devices adjustable to effective and ineffective positions independently of the operation of said manipulative devices and coöperating with the latter for determining whether a check is to be issued by the check issuing mechanism upon the 50 operation of the operating mechanism.

In testimony whereof I affix my signature in the presence of two witnesses.

MAX JACOB.
